UNITED STATES PATENT OFFICE

JOE DE GEORGE, OF ASHTABULA, OHIO

DESIGN FOR A HAT HANGER

Application filed April 23, 1931. Serial No. 39,607. Term of patent 14 years.

To all whom it may concern:

Be it known that I, JOE DE GEORGE, a citizen of the United States, residing in Ashtabula, in the county of Ashtabula and State of Ohio, have invented a new, original, and ornamental Design for a Hat Hanger, of which the following is a specification, reference being had to the accompanying drawings, forming a part thereof, in which—

I claim:

The ornamental design for a hat hanger, as shown.

Signed at Ashtabula, in the county of Ashtabula and State of Ohio, this 24th day of March, 1931.

JOE DE GEORGE.
